UNITED STATES PATENT OFFICE.

MOSES EHRENREICH, OF NEW YORK, N. Y.

DESIGN FOR A MATCH-SAFE.

SPECIFICATION forming part of Design No. 14,153, dated July 31, 1883.

Application filed June 7, 1883. Term of patent 14 years.

To all whom it may concern:

Be it known that I, MOSES EHRENREICH, a citizen of the United States, residing at New York, in the county and State of New York, have invented and produced a new and original Design for Match-Safes, of which the following is a specification.

One feature of this design is a miniature cart, and another feature a platform supporting the cart, as hereinafter more fully described.

In the accompanying drawings, Figure 1 represents a side view, and Fig. 2 a plan or top view.

15 Similar letters indicate similar parts.

The letter A designates a box of substantially rectangular shape, which represents the body of the cart, and which has rods B projecting therefrom longitudinally at one end to represent the shafts, such rods being on the lower edge and opposite sides of the box. Each side of the box A has a curved elevation, C, near the forward end, and vertical ribs I to represent side bars, while at the opposite sides of the box are arranged the cart-wheels D in a proper manner. From one of the rods B projects downwardly a bar, E, representing a brace.

30 The letter F designates a platform of substantially rectangular shape or outline, to which are connected the wheels D and the brace-bar E, it thus having the appearance of supporting the cart. The edges of this platform are stepped, as at G, and one such edge is also serrated transversely, as at H.

35 By these means I obtain a safe having a neat and characteristic appearance.

What I claim as new, and desire to secure by Letters Patent, is—

1. The design for a match-safe, consisting of 40 the box A, having end rods, B, and curved side elevations, C, and of the wheels D, as shown and described.

2. The design for a match-safe, consisting of 45 the box A, having end rods, B, and of the platform F, having its edges stepped, and one also serrated, as shown and described.

In testimony whereof I have hereunto set my hand and seal in the presence of two subscribing witnesses.

MOSES EHRENREICH. [L. S.]
